UNITED STATES PATENT OFFICE.

DELLE ERNEST RANDALL, OF SAN FRANCISCO, CALIFORNIA.

AIRPLANE.

1,369,468.

Specification of Letters Patent. Patented Feb. 22, 1921.

Application filed January 21, 1918. Serial No. 212,928.

To all whom it may concern:

Be it known that I, DELLE ERNEST RANDALL, a citizen of the United States, and a resident of the city and county of San Francisco and State of California, have invented a certain new and useful Airplane, of which the following is a specification.

The invention relates to airplanes and particularly to means for balancing the airplane.

An object of the invention is to provide an airplane which possesses inherent stability in flight.

Another object of the invention is to provide means which obviates lateral oscillation due to hunting of the balancing means.

A further object of the invention is to provide an airplane having balancing means which are automatic in action to hold the planes at the angle of equilibrium in respect to the direction of flight.

The invention possesses other advantageous features, some of which, with the foregoing, will be set forth at length in the following description, where I shall outline in full that form of the invention which I have selected for illustration in the drawings accompanying and forming part of the present specification. In said drawings I have shown one specific form of the airplane of my invention, but it is to be understood that I do not limit myself to such form, since the invention, as expressed in the claims, may be embodied in a plurality of forms.

Referring to said drawings:

Figure 1 is a perspective view of the airplane of my invention.

Fig. 2 is a plan view of the airplane.

Fig. 3 is a perspective view of a portion of the plane supporting frame.

Fig. 4 is a perspective view of the forward end of the fuselage.

Fig. 5 is a front elevation of a monoplane illustrating the application of my invention.

Fig. 6 is a front elevation of a biplane illustrating the application of my invention.

Automatic stabilizers or lateral balancing means have heretofore been proposed for airplanes for the purpose of holding them in lateral equilibrium and these devices have usually assumed the form of pendulums or comparable structures mounted on the fuselage. In all prior airplanes, as far as I am aware, the fuselage has been rigidly secured

to the planes in a lateral direction, so that the lateral balancing means have been required to effect a lateral movement of the fuselage, with its heavy load of engine, fuel, pilot, controls and other instruments. The movement of this heavy mass by the balancing means has caused the balancing means to hunt, causing thereby a lateral oscillation or wobbling of the airplane. In accordance with my invention, I arrange the fuselage, with its load, so that it has a free lateral movement with respect to the planes. The planes are, therefore, movable laterally independent of the fuselage, so that the weight of the fuselage and its load is not set in oscillation by the automatic balancing means, thereby preventing hunting of the plane structure, due to the momentum of the heavy laterally moving parts. In accordance with my invention the fuselage is pivoted or swung on the plane structure and serves as the balancing means, the weight of the fuselage and its load being such that the fuselage remains in equilibrium and thereby maintains the airplane in equilibrium. The fuselage is movable laterally with respect to the planes and this relative movement is employed to vary the angle of incidence of the planes or portions thereof in such degree and direction to cause the planes to move to reestablish equilibrium. The balancing may be effected by warping the planes at their inner, outer or intermediate portions, by changing the position of ailerons or by any other method suitable for that purpose. In the drawings I have shown the automatic balancing means arranged to warp the inner portions of the planes, but it is to be understood that I do not limit myself to this method of balancing.

The airplane of my invention consists of two structures connected together so that one has independent movement with respect to the other, one structure being the plane or supporting structure and the other being the fuselage. The plane structure comprises the frame 2 on which the plane supports, consisting in this instance of the transverse rods 3-4, are rigidly mounted. The plane ribs 5 are rigidly secured to the rods 3-4 and the planes or supporting surfaces 6-7 are formed on the ribs and cross rods. The frame 2 and the planes 6-7, therefore, form a rigid unitary structure. The frame 2 is hollow or open and the fuselage 8 is preferably arranged within the frame.

Mounted on the frame and positioned above the frame and in the plane of the longitudinal center line thereof, are aligned bearings 12-13 in which the fuselage is hung. Arranged above and secured to the fuselage 8 is a shaft 14 which is journaled in the bearings 12-13 and the supporting rods 15 are of such length that the fuselage is disposed within the frame, the frame being sufficiently wide so that the fuselage is capable of a limited swinging movement in a transverse direction within the frame. When flying a straight course, the fuselage depends vertically from its support and a tilting movement of the frame causes the angle of incidence of the planes or a portion of them to be varied to bring the planes into a horizontal position, with the fuselage suspended in the center of the frame. On making a turn, the fuselage is swung outward, causing the planes to tilt to the proper angle to produce the proper banking thereof for the turn. The inclination or banking of the planes is, therefore, automatically accomplished and the amount of banking is proportional to the sharpness of the turn and the speed of the airplane, and the pilot is, therefore, relieved of the duty of banking and uses his vertical rudder only in making turns.

The fuselage is connected to the planes in such manner that lateral movement of the fuselage with relation to the plane frame causes the plane surfaces or portions thereof to be moved to vary the sustaining power of the planes on opposite sides, so that the plane frame is moved to bring the frame into equilibrium. Secured to the fuselage is a longitudinally disposed rod 16 and journaled on opposite sides of the frame 2 are rods 17 having lever arms 18 which are connected to the rod 16 by the links 19. The rods 17 are provided with lever arms 21 which are connected to the planes, so that rotation of the rods 17 varies the angle of incidence of the planes. In the present construction, the arms 21 are connected to the inner ends of the planes by the links 22, so that equilibrium is maintained by warping the rear portions of the inner ends of the planes.

Means are provided whereby the pilot may

control the warping of the planes to alter the course of the airplane when desired and this is accomplished by manually shifting the fuselage laterally with respect to the frame, so that the planes are warped accordingly. Fulcrumed on the cross bar or cross wire 23 which is secured to and extends across the frame 2 is a lever 24, which is connected at its lower end to the fuselage, so that movement of the lever causes a shifting of the fuselage with respect to the frame.

The airplane construction is made more rigid and the fuselage is prevented from wabbling in the horizontal plane by wires 25 which connect the rear end of the fuselage with the planes at points intermediate their ends. These wires relieve the bearing 12 and 13 of any twisting strains and also reinforce the rear end of the fuselage.

The fuselage is provided with a tail provided with the horizontal and vertical rudders 26 and 27 and the fixed plane 28.

I claim:

1. In an airplane, a frame, planes attached to said frame, a shaft carried above said frame, a fuselage suspended from said shaft and arranged partly within said frame and movable laterally with respect thereto and provided with a tail extending rearwardly beyond said frame, horizontal and vertical rudders at the rear end of said tail, an engine and propeller mounted on said fuselage and means connecting the fuselage with the plane whereby movement of the fuselage with respect to the frame varies the supporting power of the plane.

2. In an airplane, a frame, planes attached to said frame, spiders secured to and arranged above said frame, journals carried by said spiders, a longitudinal shaft journaled in said bearings, a fuselage depending from said shaft whereby the fuselage has a free lateral swinging movement with respect to said frame and plane warping means connecting the planes and the fuselage.

In testimony whereof, I have hereunto set my hand at San Francisco, California, this 12th day of January, 1918.

DELLE ERNEST RANDALL.

In presence of—
H. G. PROST.
